US0D1060015S

(12) **United States Design Patent** (10) Patent No.: **US D1,060,015 S**
(45) Date of Patent: ** Feb. 4, 2025

(54) **MAGNET HOOK**

(71) Applicant: **Ningbo Zhenhai Keyda Magnet Co., Ltd.**, Ningbo (CN)

(72) Inventor: **Mingmin Chen**, Ningbo (CN)

(73) Assignee: **Ningbo Zhenhai Keyda Magnet Co., Ltd.**, Ningbo (CN)

(**) Term: **15 Years**

(21) Appl. No.: **29/951,574**

(22) Filed: **Jul. 10, 2024**
